(**) Term: **14 Years**

(57) **CLAIM**

The ornamental design for an adaptor cartridge for disposable beverage brewing package, as shown and described.

(21) Appl. No.: **29/450,003**

DESCRIPTION

(22) Filed: **Mar. 15, 2013**

FIG. 1 is a top perspective view of the design with a disposable beverage brewing package illustrated in broken lines;

(51) **LOC (10) Cl.** 07-99

FIG. 2 is a top perspective view of the design;

(52) **U.S. Cl.**

FIG. 3 is a front elevational view of the design;

USPC **D7/400**; D7/397; D9/424; D9/428

FIG. 4 is a rear elevational view of the design;

(58) **Field of Classification Search**

USPC D9/424, 428; D7/398, 400, 397;

..... D23/209; 99/295, 323

FIG. 5 is a right side elevational view of the design;

See application file for complete search history.

FIG. 6 is a left side elevational view of the design;

(56) **References Cited**

FIG. 7 is a top plan view of the design; and,

U.S. PATENT DOCUMENTS

FIG. 8 is a bottom plan view of the design with environmental structure illustrated in broken lines.

D502,362 S * 3/2005 Lazaris et al. D7/400
D520,185 S * 5/2006 Zeng et al. D28/8.1

The broken line showing is for illustrative purposes only, and

forms no part of the claimed design.
